UNITED STATES PATENT OFFICE.

KINGMAN N. CATHER, OF CHICAGO, ILLINOIS, ASSIGNOR OF ONE-HALF TO CORNELIUS J. DIRCKX, OF CHICAGO, ILLINOIS.

PAIL-TOP.

1,110,892.

Specification of Letters Patent.

Patented Sept. 15, 1914.

Application filed November 4, 1913. Serial No. 789,124.

To all whom it may concern:

Be it known that I, KINGMAN N. CATHER, a citizen of the United States, residing at Chicago, in the county of Cook and State of Illinois, have invented certain new and useful Improvements in Pail-Tops, of which the following is a specification.

The present invention relates to a cover or top, adapted for use upon pails of various sizes and styles, whereby the pail is rendered adaptable for use as a minnow bucket.

The objects of the present invention are: To provide a top of the class described, which is of a nature adapted to be transported from place to place without inconvenience; to so construct the top as to enable it to be used with any sort of a pail or container; to form the major portion of the device from a flexible material, whereby it may be rolled or folded into a compact package; to provide the top with a bag or retaining member of flexible material; to provide means for raising the bag portion of the device out of the water to enable the user to readily procure any particular minnow that he may desire; to provide suitable weights for the bucket or bag portion to insure its becoming submerged in the water; to provide means for firmly and securely holding the top in place, whereby the pail may be placed in the lake or stream if desired, and to insure against the door in the top opening up when so placed; to surround the hole or opening formed in the top with a metallic frame, thereby stiffening the opening and also forming a means for mounting the covering or door in position; to place a series of holes in said top at different distances from the center, whereby the top may be secured to any and all sizes of pails with which it could be suitably used, and to utilize the holes as air openings.

The invention further consists in the features of construction and combinations of parts hereinafter described and claimed.

In the drawings: Figure 1 is a view of the top of the present invention in operative position upon a water container or pail; Fig. 2 is a vertical section of the parts shown in Fig. 1, and showing the door of the top in raised position, and illustrating how the bag or container portion of the device is raised out of the water; Fig. 3 is a plan view of the form of top illustrated in Figs. 1 and 2; Fig. 4 is a plan view of a

modified form of top; Fig. 5 is a cross section through the form shown in Fig. 1 as applied to a small sized part; Fig. 6 is a plan view of a second modified form of top; and Fig. 7 is a cross section through the form shown in Fig. 6.

In the art to which the present invention relates, the form of minnow bucket now used, so far as I am aware, is in the nature of a metallic outer pail of impervious construction, which is intended to contain the water, and an inner compartment also formed of metal, which is of a perforated or foraminous construction, and is designed to contain the fish. This form of device, however, is subjected to very serious criticism of bulk. That is, it is cumbersome and undesirable to transport from place to place, and frequently, rather than carry the contrivance back and forth, the user will abandon the device and buy a new one next season, thereby making their use costly. The present invention is intended primarily to overcome this salient defect in the prior constructions, and to produce a simple device, small of bulk and easily carried, which may be employed with any form of pail to enable the pail to be used as a minnow bucket, thus eliminating the transporting from place to place of the present bulky device now used for that purpose.

Referring now to the drawings, and particularly to Figs. 1 and 2, the device as there shown consists of a bag portion 8 preferably formed of an open weave fibrous material, flexible in nature, whereby it may be wrapped into a small space. As shown in Fig. 1, this bag portion, when in use, extends downward in the form of a bag or sack, and this portion of the device, when used, confines the bait for a purpose herein-after explained. This body or bag portion is attached to what may be termed an upper portion or top 9, which forms the gist of the present invention. This top consists of a horizontally extending section 10 and a vertically extending section 11 in the form of a skirt. The major portion of this top 9 is preferably constructed of canvas or some other flexible material, and the horizontal section of the top is formed with an opening 12, which opening is surrounded by a metal frame 13, which, in the form shown in Figs. 1, 2, and 3, is triangular in nature. This particular formation is desirable be-

cause of the ability to construct the same of small scraps of material. Secured to this metal frame by a hinge 14 or otherwise is a cover 15 for the opening 12, which cover 5 consists of an outer metal frame 16 inclosing a screen or a foraminous portion 17, and this cover, in the construction shown, is held in closed position through the instrumentalities of a catch member 18 se- 10 cured to the metal frame-work 13. The skirt or depending portion 11 of the top sec- 15 tion 9 is, as stated, made of some sort of flexible material, and in the construction shown it is provided with suitable draw- 20 strings 19 by the manipulation of which the skirt can be drawn tightly against the upper portion of the pail. The device, when in operative position as shown in Figs. 1 and 2, is attached to a bucket 20 which can be 25 of any suitable size and construction.

One of the main features of the present invention is its adaptability to be attached and used with almost any form and size of bucket, because the skirt 11 can accom- 25 modate itself to any size required, and can be fitted and placed upon every size and form of bucket which could be practically used as a minnow bucket. Therefore, the user does not have to carry from place to 30 place a large and cumbersome bucket of a special design and size, but need simply carry the top of the present invention, and when he reaches his destination, he can use this top upon any sort of bucket that may 35 be available.

The method of attaching the top to the bucket is obvious from the foregoing de- 40 scriptions and from a study of the draw- 45 strings. The horizontal portion is placed on top of the pail and the skirt upon the outer upper edge, and the draw-strings are pulled or adjusted so as to pull the skirt tightly about the upper portion of the bucket, and thus the top is maintained in the proper po- 50 sition thereupon.

In using minnow buckets, the user will frequently desire to obtain a particular minnow of the number in the bucket, and heretofore it has been a matter of difficulty to 55 select a particular minnow from the mass, and in the selecting operation injury frequently results to some of the other minnows by reason of rough handling. In the present invention, I make use of the bag portion 8 of the device to eliminate this difficulty, and, in fact, it is in this connection that the value of the bag portion of the invention lies. I supply a cord 21 which is attached to the bottom of the bag portion 60 8, and this cord may, if desired, be attached to the cover 15, as shown in Figs. 1 and 2. If this method is employed, then whenever the cover 15 is raised the bottom of the bag will be drawn upward toward the opening 65 12, as shown in Fig. 2, raising the major

part of the bag out of the water and bring- 70 ing the minnows close to the opening 12, whereby the extraction of any particular minnow is rendered easy and without any rough handling which would in any way injure any one of the mass of minnows. A weight 22 is shown as attached to the bottom portion of the bag or container portion 8 for the purpose of submerging the bag in 75 the water.

It is understood that the bag attachment is placed on the top merely for the purpose of expediting the removal of the minnows from the pail, but so far as transforming the ordinary pail into a minnow bucket is 80 concerned, the top section, which is the gist of the present invention, is sufficient by itself for this purpose, and when applied to the upper portion of the pail will convert the pail into a practical minnow or fish 85 bucket. This top section, as stated, consists of a horizontal section 10 and a vertical sec- 90 tion 11 depending therefrom, this latter section being in the form of a skirt. The horizontal and vertical sections are formed of a single piece of suitable flexible material, as, for instance, canvas. The skirt portion is divided at two points oppositely disposed to one another, and openings 23 are formed at these points of division. These openings 95 are arranged to align with the bail of the bucket, and so enable the top to be attached to the pail without eliminating any of the usefulness of the bail.

Adjacent to the free ends of the skirt sec- 100 tion are eyelets 24 of suitable construction, which eyelets receive lacing cords 19 for the purpose of drawing the skirt tightly around the upper end of the pail when the top is attached thereto. The horizontal portion of the top is provided with a series of eyelets 105 26 which serve as air openings to admit air into the interior of the pail, and also serve, as shown in Fig. 5, as lacing eyelets when the top is applied to a pail having a rim of 110 small diameter. It will be readily under- 115 stood, by referring to Fig. 5, how these eye-lets 26 are thus utilized. A portion of the horizontal section is folded down over the top of the bucket to place it in a vertical plane, and the eyelets 26 are used for the purpose of receiving the lacing cord, so that, with a plurality or sets of eyelets as are thus provided, it enables the device to be at- 120 tached to a large variety of sizes of pails, and sufficient latitude is allowed to enable the top to be attached to any form of bucket which would be practical for the purpose of carrying minnows.

In order to allow the top to accommodate 125 itself to buckets of various sizes, I place one or more V-shaped notches 27 in the horizontal portion and in alinement with the opening 23 in the depending skirt and into such V-shaped notch or notches is inserted a gus- 130

set 28 of suitable fabric, thereby giving to the horizontal portion a consideration latitude in allowing it to adjust itself to the pail top. These gussets are alined with the openings 23 and will come opposite the bails when the top is attached, and will, therefore, allow of the securing of the top into position without any undue wrinkling by reason of the presence of the bail. The foregoing 10 description has been confined to the form of device in Figs. 1, 2, 3, and 5.

Referring now to Fig. 4, the form therein shown is in all respects similar to the form heretofore described, save that a door 29 for 15 closing the opening in the horizontal portion of the top is shown, which is intended to swing about a pivot 30, as shown by the dotted lines, and a hinge clasp 31 is employed, which, in combination with an eye 20 32, forms the means for holding the door in place.

The form shown in Figs. 6 and 7 is in all respects similar to that described in connection with the description of the form shown 25 in Figs. 1, 2, 3, and 5, except that a square door 33 is employed mounted upon hinges 34, and the metal frame about the opening in the horizontal portion of the top is made from a wire 35 bent into the form of a 30 square frame, and, as shown, is surrounded by the fabric. In all these figures, a cord 36 may be employed, which, when passed through the eyelet or catch member 18, serves to hold the door in closed position. It 35 will be readily understood that, with the top of the present invention applied in the manner described to a pail, the said pail is then converted into a minnow bucket, and can be placed into the lake or stream, as is customary with ordinary minnow buckets, without 40 any danger of the fish escaping, and will serve every purpose and function of the minnow bucket now used, but will entirely eliminate the objectionable feature of bulk 45 which is present in ordinary and well known types of minnow bucket. The top can be readily and easily transported from place to place, being adapted to be folded into a compact parcel, and the top can be used 50 with every style and size of bucket which would be practical for the purpose of carrying minnows.

I claim:

1. A device of the class described, comprising a depending body portion of flexible foraminous material and a top section secured thereto, said top section consisting of a horizontal portion and a skirt of flexible material vertically depending therefrom, 55 said horizontal portion having an opening, a cover for said opening, and means for drawing the depending skirt to a desired size, substantially as described.

2. A device of the class described, comprising a depending bag-like portion of 60

open-weave fabric and a top section secured thereto, said top section consisting of a horizontal portion and a skirt of flexible material vertically depending therefrom, said horizontal portion having an opening 70 therein, a metal frame about the opening a cover for said opening, having a fabric body, a metal frame for said body, and means for drawing the depending skirt to a desired size, substantially as described. 75

3. A device of the class described, comprising a depending bag-like portion of open-weave fabric and a top section secured thereto, said top section consisting of a horizontal portion and a skirt of flexible 80 material vertically depending therefrom, said horizontal portion having an opening therein, a cover for said opening, means for drawing the depending skirt to a desired size, and means for drawing the bottom of 85 the bag-like portion toward said opening, substantially as described.

4. A device of the class described, comprising a depending bag-like portion of open-weave fabric and a top section secured 90 thereto, said top section consisting of a horizontal portion and a skirt of flexible material vertically depending therefrom, said horizontal portion having an opening therein, a cover for said opening, means for 95 drawing the depending skirt to a desired size, and means for drawing the bottom of the bag-like portion toward said opening when said cover is lifted, substantially as described. 100

5. A device of the class described, comprising a depending bag-like portion of open-weave fabric and a top section secured thereto, said top section consisting of a horizontal portion and a skirt of flexible material vertically depending therefrom, said horizontal portion having an opening therein, a cover for said opening, a cord connected to said cover and the bottom of the bag-like section, whereby, when the cover is lifted, 105 the bottom of the bag-like portion is pulled upwardly toward said opening, substantially as described. 110

6. A device of the class described, comprising a depending bag-like portion of open-weave material, a weight on the bottom of said bag, a top section secured to said bag, said top section consisting of a horizontal portion and a skirt of flexible material vertically depending therefrom, said horizontal portion having an opening therein, a cover for said opening, and means for drawing the depending skirt to a desired size, substantially as described. 115

7. A device of the class described, comprising a depending bag-like portion of open-weave fabric and a top section secured thereto, said top section consisting of a horizontal portion and a skirt of flexible material vertically depending therefrom, said 120 125 130

- horizontal portion having an opening therein, a cover for said opening, and a draw-string for drawing the depending skirt to a desired size, substantially as described.
- 5 8. A device of the class described, comprising a depending bag-like portion of open-weave fabric and a top section of fabric secured thereto, said top section consisting of a horizontal portion formed with a 10 vertically depending skirt, said horizontal section having an opening therein, a metal frame around said opening, a cover secured to said frame, and means for drawing said skirt portion to a desired size, substantially 15 as described.
9. A device of the class described, comprising a horizontal section provided with an opening, a cover for the opening, a section made of flexible material vertically dependent from the horizontal section, and means for drawing the vertical section to a desired size, substantially as described.
10. A device of the class described comprising a horizontal section and a vertical 25 flexible section depending therefrom, said horizontal section having an opening therein, a cover for closing said opening, a series of members adapted to receive draw strings and said members being arranged at different 30 distances from the center of said device, substantially as described.
11. A device of the class described made of flexible material and comprising a horizontal section and a vertical section depending therefrom, said horizontal section having an opening therein, a metal frame about 35 said opening, a cover for closing said opening, and means for drawing the vertical section to a desired size, substantially as described.
12. A device of the class described made of flexible material and comprising a horizontal section and a vertical section depending therefrom, a portion of the vertical section being cut away, said horizontal section 45
- being formed with a notch alined with the cutaway portion of the vertical section, a gusset inserted in said notch, said horizontal section having an opening therein, and a cover for closing said opening, and means 50 for drawing the vertical section to a desired size, substantially as described.
13. A device of the class described made of flexible material and comprising a horizontal section and a vertical section depending therefrom, eyelets in the vertical section to receive a draw-string, eyelets in the horizontal section forming air inlets and also adapted to serve as draw-string eyelets, said horizontal portion having an opening 55 therein for permitting access to the interior of the pail, and a cover for closing said opening, substantially as described.
14. A device of the class described formed of flexible material and comprising a horizontal section and a vertical section depending therefrom, said vertical section being made in two parts with their ends spaced apart, said horizontal section having a notch therein alined with one of said spaces, a 60 gusset in said notch, eyelets in the vertical section to receive a lacing cord, eyelets in the horizontal section serving as air inlets and also adapted to serve as draw-string eyelets, said horizontal section having an opening 65 therein, and a cover for closing said opening, substantially as described.
15. A device of the class described formed of flexible material and comprising a horizontal section and a vertical section depending therefrom, said horizontal section having an opening therein, a cover for said 70 opening, eyelets in the horizontal section forming air inlets and also adapted to serve as draw-string eyelets, substantially as described.
